UNITED STATES PATENT OFFICE.

JOHN H. REYNOLDS, OF TROY, NEW YORK.

DUST-GUARD FOR RAILWAY-CAR WINDOWS.

SPECIFICATION forming part of Letters Patent No. 257,068, dated April 25, 1882.

Application filed December 3, 1881. (No model.)

To all whom it may concern:

Be it known that I, JOHN H. REYNOLDS, of Troy, in the county of Rensselaer and State of New York, have invented certain new and useful Improvements in Dust-Guards for Car-
5 Windows, of which the following is a specification.

My invention relates to improvements on the devices described in the Letters Patent of the 10 United States, Nos. 211,523 and 218,064, granted to me, respectively, on January 21, 1879, and July 29, 1879; and the objects of these present improvements are, first, to render the dust-guards described in my aforesaid patents automatic in their action; second, to provide for 15 said dust-guards hinges adapted to lock them sufficiently secure to prevent any rattling noise, but free enough to permit the guards to be automatically extended and closed back by 20 the resistance of the air when the car is moving; and, third, to furnish additional support to the middle portion of the guard for the purpose of preventing the pressure of the air against its back while in an extended position 25 from bending the guard, and thereby opening the joint between it and the flange of its guard-strip. These objects I attain by means of the devices illustrated in the accompanying drawings, which form part of this specification, and 30 in which—

Figure 1 is a front elevation of the guard-strip and its attached parts; Fig. 2, a side elevation of the socket-piece of the hinge with a hinge-pintle in position for holding the dust- 35 guard extended from the side of the car; Fig. 3, a horizontal section through the guard-strip and dust-guard with the latter extended perpendicularly to the side of the car; Fig. 4, a front elevation of the socket-piece with a hinge- 40 pintle in position for holding the dust-guard closed back toward the side of the car; and Fig. 5, a horizontal section through the guard-strip and dust-guard, with the latter thrown back from the window so as to lie in line with 45 the side of the car.

As illustrated in the drawings, my improved hinge for the dust-guard consists of a socket-piece, A, and a pintle, C, constructed in the following manner: The socket-piece A is provided with a socket, a, for receiving the pintle of the hinge. Said socket has in its upper

end, at one or both sides and in front, V-shaped depressions a'. Preferably I form the said depressions in both of the opposite sides and in front, so as to adapt the socket-pieces for use 55 at the right or left side of the car-window. The socket-pieces A are secured in place between the standing flanges b of the guard-strip B, as fully described in my Patent No. 218,064, above referred to. The pintle C is 60 cylindrical in form, and is provided with a pendent V-shaped projection, e, adapted to engage in the depressions a' of the socket a; and preferably I arrange the said pendent projection to lie against the back side of the dust-guard. A square shoulder, c', is formed on the 65 top of the pintle C to strike against the flange a' of the socket-piece, as shown in Fig. 5, and prevents the outer edge of the dust-guard from being thrown back against the side of the car 70 to rub against and mar the paint thereon. By this means the dust-guard is maintained in position, while turned back, where the air-currents produced by the motion of the car will 75 "bank up" between the side of the car and the back of the dust-guard until sufficient pressure is accumulated to force the dust-guard to turn on its hinges into its extended position.

D is an inclined lip or guide, secured near the middle of each guard-strip B and projecting outward through the flange b, lying next to the window-opening. Said lip is adapted to guide the inner edge of the dust-guard into place whenever the said guard is turned into its extended position; and it also serves as 80 a support for holding the inner edge of the dust-guard snugly against the face of the adjoining flange b, and thus prevents the joint between the dust-guard and the guard-strip from being forced open by the pressure of the 85 air to admit the dust therethrough to enter in at the window.

E is a dust-guard constructed in the manner described in my prior patents, herein referred to, and having the pintles C, as above 95 described, secured thereto.

This improvement avoids the necessity of raising the dust-guard (as described in my Patent No. 211,523) before turning it on its hinges, and by it the dust-guards are adapted to open 100 and close automatically by the resistance offered by the air while the car is moving in

either direction, and in such manner that the dust-guards fixed at the window sides lying toward the head of the train will be automatically extended to exclude the dust from the windows, and those fixed at the farther side of the windows will be closed back toward the side of the car. At the first phase of the turning movement of the pintle in its socket the angular side of the projection *c* by bearing against the inclined side of the depression *a'* causes the dust-guard to rise up until the lowest point of said projection is high enough to pass over the top of the socket *a*, and then by the continued turning movement the projection is brought into position to drop into the next depression, wherein it will be held with sufficient tenacity to prevent the parts from making any rattling noise.

While I have shown and described the depressions *a'* and projection *c* as being made with a V-shaped outline, it is obvious that either or both of them may be made with curvilinear edges to produce the same effect.

I claim as my invention—

1. A dust-guard for railcar windows, adapted to open and close automatically, as herein described, and provided with self-locking hinges adapted to secure the said dust-guard in position when turned in a perpendicular line to the side of the car and when

thrown back from the window in line with the side of the car, substantially as herein specified.

2. The combination, with a dust-guard, *E*, of hinges composed of a socket, *a*, provided with depressions *a'*, formed in the front and two sides of said socket, as herein described, and a pintle, *C*, provided with a pendent projection, *c*, for the purpose of locking said dust-guard in position when projected perpendicularly from the side of the car and when thrown back from the window in line with the side of the car, and for raising said guard in the first phase of a turning movement, as herein specified. 40

3. In a dust-guard hinge, the pintle *C*, provided with a shoulder, *c'*, adapted to strike against the socket-piece *A* for the purpose of preventing the outer edge of the dust-guard from striking against the side of the car, as 45 herein specified.

4. The guard-strip *B*, provided with a lip, *D*, arranged as herein described, for the purpose of guiding and retaining the inner edge of the dust-guard against the face of the conjoining flange *b*, as herein specified. 50

JOHN H. REYNOLDS.
